INVENTOR

UNITED STATES PATENT OFFICE

ARTHUR C. HOPKINS, OF NILES, MICHIGAN, ASSIGNOR TO NATIONAL STANDARD COMPANY, OF NILES, MICHIGAN

LIFTING JACK

Application filed April 1, 1927. Serial No. 180,192.

The main objects of this invention are:

First, to provide an improved lifting jack which is very compact when collapsed and at the same time has a considerable lift.

5 Second, to provide an improved lifting jack which is very powerful.

Third, to provide an improved lifting jack having screw extension means in which the threaded parts are completely housed.

10 Objects relating to details and economies of construction and operation of my invention will appear from the detailed description to follow.

The invention is defined and pointed out in 15 the claims.

A structure which is a preferred embodiment of my invention is illustrated in the accompanying drawing, forming a part of this specification, in which:

20 Fig. 1 is a detail view mainly in vertical section of my improved lifting jack collapsed, on line 1—1 of Fig. 2.

Fig. 2 is a horizontal section on a line corresponding to line 2—2 of Fig. 1.

25 Fig. 3 is a detail section on a line corresponding to line 3—3 of Figs. 1 and 4.

Fig. 4 is a fragmentary side elevation of my improved lifting jack extended, parts being broken away to show structural details.

30 In the embodiment of my invention illustrated, the standard 1 is provided with a gear housing 2 at its lower end, and with a peripheral flange 3 resting upon and secured to the base plate 4 by the bolts or rivets 5.

35 This standard has internal screw threads 6 and an inturned flange 7 at the top, the flange having opposed notches 8 therein.

The driving spindle 9 is disposed vertically within the standard, its lower end being 40 journaled at 10 in the base plate, the spindle being provided with a beveled gear 11. The driving pinion 12 is arranged to mesh with this gear 11, the driving gear being journaled in the bearing 13 of the gear housing 45 and provided with a socket 14 adapted to receive the shaft 15 of a crank.

On the spindle is a driving screw 16 having a lower or bottom portion 17 coacting with the threads of the standard. The screw 50 has a threaded barrel-like upper portion 18

with which the internal threads 19 of the lifting member 20 coact. This barrel-like portion 18 is reversely threaded relative to the threads of the portion 17.

The lifting member 20 is tubular to telescope with the portion 18 of the screw and is provided with a head 21 at its upper end.

The lifting member is provided with a longitudinal rib 22 which engages the notch 23 in the inwardly turned flange 24 in the upper end of the sleeve-like housing 25, this sleeve being telescopingly associated with the standard and with the lifting member. The rib 22 engaging the notch 23 prevents rotation of the lifting member relative to the sleeve; the sleeve in turn is held against rotation by its longitudinal ribs 26 which engage notches 8 in the inturned flange 7 at the upper end of the standard.

The lifting member has an out-turned flange 27 coacting with the inturned flange 24 of the housing sleeve to provide stops.

The out-turned flange 28 at the lower end of the sleeve engages the flange 7 of the standard to provide stops, so that the sleeve member 25

70 performs the function of a housing enclosing the screw, a stop limiting the extension of the jack and supporting the lifting member against rotation so that as the screw is rotated through the spindle, it not

only travels up in the standard owing to the engagement of its threaded portion 17 with the threads of the standard, but the lifting member is simultaneously projected, so that I not only provide a jack which is very powerful but one which is rapidly extended and retracted.

85 I have illustrated and described my improved jack in an embodiment which I consider very practical. I have not attempted to illustrate or describe certain adaptations and embodiments which I contemplate as I believe this disclosure will enable those skilled in the art to embody or adapt my improvements as may be desired.

90 Having thus described my invention, what I claim as new and desire to secure by Letters Patent, is:

1. In a lifting jack, the combination of an internally threaded standard having an in-

wardly projecting flange at its upper end, a vertically disposed driving spindle rotatably mounted in said standard and provided with a beveled gear at its lower end, a driving gear mounted on said standard to coact with said gear on said spindle, an actuating screw having splined driving engagement with said spindle and provided with a threaded lower portion coacting with the threads of said standard and with an oppositely threaded upper portion, a hollow lifting member telescopingly associated with the upper portion of said actuating screw and having threaded engagement therewith, said lifting member having an out-turned flange at its lower end and a longitudinal rib, and a housing sleeve embracing said upper portion of said screw and telescopingly associated therewith and with said standard, said sleeve having an out-turned flange at its lower end coacting with the inturned flange at the top of said standard, and an inturned flange at its upper end coacting with said flange at the lower end of said lifting member, said flanges coacting to provide stops, said sleeve having a longitudinal rib, said flange on said sleeve being notched to coact with said rib on said lifting member and said flange on said standard being notched to coact with said rib on said sleeve whereby the sleeve and lifting member are supported against rotation.

2. In a lifting jack, the combination of an internally threaded standard having an inwardly projecting flange at its upper end, a vertically disposed driving spindle rotatably mounted in said standard, an actuating screw having splined driving engagement with said spindle and provided with a threaded lower portion coacting with the threads of said standard and with an oppositely threaded upper portion, a hollow lifting member telescopingly associated with the upper portion of said actuating screw and having threaded engagement therewith, said lifting member having an out-turned flange at its lower end and a longitudinal rib, and a housing sleeve embracing said upper portion of said screw and telescopingly associated therewith and with said standard, said sleeve having an out-turned flange at its lower end coacting with the inturned flange at the top of said standard, and an inturned flange at its upper end coacting with said flange at the lower end of said lifting member, said flanges coacting to provide stops, said sleeve having a longitudinal rib, said flange on said sleeve being notched to coact with said rib on said lifting member and said flange on said standard being notched to coact with said rib on said sleeve whereby the sleeve and lifting member are supported against rotation.

3. In a lifting jack, the combination of an internally threaded standard, a vertically disposed driving spindle, an actuating screw having splined driving engagement with said

spindle and provided with a threaded lower portion coacting with the threads of the standard and with an oppositely threaded upper portion, a lifting member having threaded engagement with the upper portion of the screw and provided with a longitudinal rib, and a housing member telescopingly associated with said standard and lifting member and provided with a longitudinal rib and with stop means coacting with said standard and lifting member, said housing member having means coacting with said rib on said lifting member to prevent rotation of the lifting member, said standard having means coacting with said rib on said housing member to prevent rotation of the housing member.

In witness whereof I have hereunto set my hand.

ARTHUR C. HOPKINS.
